DIPPING MACHINE

William T. Green, Newark, N. J., assignor to
 Maas & Waldstein Co., Newark, N. J., a corporation of New Jersey

Application June 26, 1934, Serial No. 732,405

5 Claims. (Cl. 91—46)

This invention relates, generally, to the coating of articles with lacquers, varnishes, and etc., and the invention has reference, more particularly, to a novel dipping machine for dipping articles in lacquers or other coating compositions for the purpose of coating the articles.

Dipping machines heretofore used for coating articles have generally been somewhat unsatisfactory in use owing to the tendency of such machines to form rings or ridges on the articles coated due largely to vibrations set up by motor driven gearing, etc. Also, such machines oftentimes operate at improper speeds resulting in the streaking, sagging, running or wrinkling of the lacquer or other coating material, thereby greatly detracting from the appearance of the articles coated.

The principal object of the present invention is to provide a novel dipping machine that is so constructed and arranged as to overcome the above objections, the said machine being adapted to rapidly produce perfectly coated objects in quantity.

Another object of the present invention lies in the provision of a novel dipping machine of the above character having means for elevating and lowering the container of coating material with respect to the work or articles being coated, the latter being held stationary.

Still another object of the present invention is to provide a novel dipping machine of simple, rugged and reliable construction, the said machine being easily operated and economically maintained.

Other objects of this invention, not at this time more particularly enumerated, will be clearly understood from the following detailed description of the same.

The invention is clearly illustrated in the accompanying drawings, in which:

Fig. 1 is a view in front elevation of the dipping machine, the front panel of the machine being broken away to better illustrate the construction of the machine.

Fig. 2 is a view in side elevation of the machine, one side panel being broken away to better illustrate the machine.

Fig. 3 is a plan view of the machine with parts broken away.

Fig. 4 is a sectional view taken along line 4—4 of Fig. 3 looking in the direction of the arrows and illustrating the machine in operation, and

Fig. 5 is a front perspective view of the structure shown in Fig. 4 with the coating material container broken away.

Similar characters of reference are employed in said views to indicate corresponding parts.

Referring now to the said drawings, the reference numeral 1 designates the frame of the dipping machine which consists essentially of four angle bar uprights that are interconnected and braced by horizontal angle bars 2. A table 3 is fixed upon the top of the frame 1. Upstanding brackets 4 are mounted upon the end portions of table 3, the said brackets 4 being adjustable within limits longitudinally of table 3 by means of bolts 20 and slots 36.

Two of the brackets 4 are mounted on each end portion of the table 3 and are interconnected by horizontal bars 5 that are attached at their ends to the brackets 4 as by wing bolts 6. The wing bolts 6 extend through any selected horizontally aligned pair of a plurality of vertically spaced apertures 7 provided in the two brackets 4 at each end of the table. Thus, by removing wing bolts 6 from one pair of apertures 7 and inserting them in another lower or higher pair of apertures 7, the bars 5 may be raised or lowered.

The bars 5 are adapted to support a horizontal panel 8 provided preferably with a plurality of apertures 9 that may be of various sizes for frictionally receiving and supporting stems 10 carrying suspended work pieces or articles 11 to be coated (see Figs. 4 and 5). A coating material container 12 is adapted to be positioned below the panel 8, the said container 12 being mounted upon a vertically movable rectangular platform 13. Platform 13 is fixed upon the upper end of a piston rod 14 that extends downwardly through an aperture in table 3, through the upper head or end of a hydraulic cylinder 15, and has a piston 16 fixed to its lower end for reciprocating within cylinder 15. As especially shown in Fig. 4 the piston 16 is preferably provided with a downwardly directed cup leather 17 for preventing the passage of water upwardly past the piston 16.

The platform 13 is illustrated as provided adjacent its corners with depending guide rods 18 that are fixed to the under surface of platform 13 and extend downwardly through slide bearings 19 mounted in apertures in the table 3. Guide rods 18 and slide bearings 19 cooperate with piston rod 14 in controlling the movement of platform 13 so that this platform moves up and down smoothly, freely and without vibration in use.

The dipping machine is illustrated as having front and rear walls 21 and 22 and side walls 23 attached to the frame 1 thereof. Water supply piping 24, that is adapted to be connected to the city or town water mains (not shown), extend

horizontally through an aperture provided in a side wall 23 of the machine. A quick operating valve 25 is positioned behind front wall 21 and is connected in pipe 24. Valve 25 has a forwardly projecting operating arm 26 that projects through a slot provided in the front wall 21 to enable ready manual actuation of this arm by the machine operator. Arm 26 is illustrated as connected by a chain 27 to a rod 28 projecting from the platform 13.

Within the machine, the water supply piping extends downwardly at 24' and has a valve 29 therein operated by a handle 30 positioned in front of wall 21, the shank of handle 30 projecting through an aperture in front wall 21. Near the bottom of the machine, the water supply piping again extends horizontally of the machine at 24" and through the side wall 23, said piping having a discharge end 31 connected to a suitable outlet drain. A branch pipe 32 connects the piping 24" to the bottom of cylinder 15. A valve 33 is connected in piping 24" between branch pipe 32 and discharge end 31. Valve 33 has an operating handle 34 positioned in front of wall 21, the shank of the handle extending through an aperture in front wall 21. A pipe 37 connects the upper end or head of cylinder 15 with piping 24" at a point between valve 33 and discharge end 31.

30 In use, valve 29 regulates the up speed of the platform 13, whereas the valve 33 regulates the down speed of the platform and hence that of the coating material container 12. Assuming that it is desired to coat the articles 11 suspended 35 from the panel 8, the container 12 is first filled with the coating composition 35 such as a suitable lacquer while the platform 13 is in its lowest position. With the platform 13 and container 12 in their lowest positions, the articles 11 are suspended above the surface of the coating composition 35. Valve 33 is turned preferably to almost closed position and valve 29 is opened an amount depending upon the desired up or dipping speed of the machine.

45 The operating arm 26 of the quick opening valve 25 is now depressed, thereby allowing water to flow through piping 24 past valve 29, through branch pipe 32 and into the bottom of cylinder 15. Hydraulic pressure thus created within cylinder 15 causes piston 16 to move upwardly, thereby raising piston rod 14 and platform 13 so that the container 12 is raised, causing the coating material 35 therein to gradually surround the articles 11 as shown in Fig. 4. When 50 the articles 11 are completely submerged in the coating material 35, the arm 26 is raised, thereby shutting off the supply of water and permitting the water within cylinder 15 to gradually flow out of this cylinder through branch pipe 32, valve 33 and pipe discharge end 31.

55 The extent of opening of valve 33 determines the lowering or withdrawal speed of the container 12, and it is important that this speed should be somewhat slower than the natural speed of flow of the coating composition, or else rings or wrinkles will be formed on the articles 11. Any water leaking up past piston 16 is conveyed by pipe 37 to the discharge end of piping 24".

70 In practice, the up or dipping speed of the container 12 is usually faster than the natural speed of flow of the coating composition while the lowering or withdrawal speed is slower than the speed of flow of the coating composition. 75 Since valve 33 is open somewhat at all times, the

escape of a limited quantity of water through this valve while piston 16 is rising serves to cushion any water hammer that may occur in the water supply piping so that container 12 is raised steadily and without jarring. When chain 27 is employed, its length will automatically determine when the container 12 will start to descend.

The lowering or withdrawal movement of container 12 is extremely steady and smooth since this container descends solely by gravity, the speed of descent being easily set or determined by the adjusting of valve 33. This steady downward movement of the container 12 is conducive to the production of perfectly coated objects 11, since no motor means is operating to set up vibrations in the coating liquid 35 which would produce rings or wrinkles on the work. After the articles 11 have been coated the panel 8 may be removed and another panel 8 carrying objects to be coated, substituted in its place. Thus, the output of the machine is very large for each reciprocation of the piston 16 effects a coating operation.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

I claim:—

1. In a dipping machine of the character described, a vertical hydraulic operating cylinder, 35 piping connecting said cylinder to a supply of water under pressure and to a drain, a piston reciprocatable within said cylinder, a piston rod extending upwardly from said piston and through the top of said cylinder, a container carrying platform mounted on the top of said piston rod, a container on said platform, and stationary work carrying means positioned above said platform, whereby upward movement of said piston due to the admission of water under pressure from said piping causes said container to rise so that coating liquid therein will envelop work supported by said work carrying means, some of the water under pressure escaping through said piping to the drain during the upward movement of said piston, 50 thereby preventing the formation of ripples on the liquid surface of said container and hence producing perfect coating.

2. In a dipping machine of the character described, a vertical hydraulic operating cylinder, 55 piping connecting said cylinder to a supply of water under pressure, valve means connected in said piping for controlling the supply of water to said cylinder, a piston within said cylinder and having a piston rod extending upwardly and out through the top of said cylinder, a container carrying platform mounted on the top of said piston rod, a coating material container on said platform, and stationary work carrying means positioned above said platform, whereby one operation of said valve 60 means admits water under pressure to the underside of said piston and serves to effect upward movement of said piston and said container so that the coating liquid therein envelops work depending from said work carrying means, means for steadyng said upward movement and another operation of said valve means allows the gradual escape of water from below said piston and serves to effect the lowering of said piston and said container by gravity so that the coating liquid is 70 75

withdrawn from the work, the upward and lowering speeds of said container being determined by the setting of said valve means, said speeds being respectively faster and slower than the natural speed of flow of the coating liquid used. 5

3. In a dipping machine of the character described, a hydraulic cylinder, a piston movable within said cylinder and having a piston rod extending upwardly and out of said cylinder, a coating material container carried upon the top of said piston rod, a stationary work holding member positioned above said container, piping connecting the bottom of said cylinder to a source of water under pressure and to a drain, valves connected in said piping for controlling the flow of water under pressure to said cylinder beneath said piston and for controlling the flow of water from said cylinder to the drain, whereby said piston and hence said container may be raised and lowered at desired predetermined speeds to effect the coating of work carried by said work holding member, the valve connecting said cylinder to the drain being continuously open whereby water hammer is eliminated and perfect coating of articles is obtained. 25

4. In a dipping machine of the character described, a hydraulic cylinder, a piston movable within said cylinder and having a piston rod extending upwardly and out of said cylinder, a coating material container carried upon the top of said piston rod, a stationary work holding member positioned above said container, piping connecting the bottom of said cylinder to a source of water under pressure and to a drain, adjustable valves connected in said piping, one of said valves serving to control the rate of flow of water under pressure to said cylinder beneath said piston for raising said container and another of said valves serving to control the rate of flow of water therefrom and hence the rate of lowering said container under the action of gravity, whereby the ascending and descending speeds of said piston and the container carried thereby may be predetermined to suit the requirements of any particular job, the valve connecting said cylinder to the drain being continuously open whereby water hammer is eliminated and perfect coating of articles is obtained. 5

5. In a dipping machine of the character described, a hydraulic cylinder, a piston movable within said cylinder and having a piston rod extending upwardly and out of said cylinder, a coating material container carried upon the top of said piston rod, a work holding member positioned above said container, piping connecting the bottom of said cylinder to a source of water under pressure and to a drain, adjustable valves connected in said piping, one of said valves serving to control the rate of flow of water under pressure to said cylinder and another of said valves that is continuously open serving to control the rate of flow of water therefrom, and a quick operating valve connected in said piping in advance of said adjustable valves for controlling the admission of water to said cylinder, the opening of said quick operating valve serving to admit water to said cylinder for raising said piston and hence said container so that the coating material therein will coat work carried by said work holding member, the sudden flow of water under pressure being cushioned by the escape of some water to the drain, whereby smooth movement of the container results, and the closing of said quick operating valve serving to shut off the supply of water to said cylinder, and enabling the water therein to drain out through said piping, thereby effecting the lowering of said container by gravity, said adjustable valves respectively determining the ascending and descending speeds of said container. 10 15 20 25 30 35
